UNITED STATES PATENT OFFICE.

ERWIN R. STOEKLE, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRICAL REGULATOR.

Application filed November 22, 1920. Serial No. 425,711.

To all whom it may concern:

Be it known that I, ERWIN R. STOEKLE, a citizen of the United States, residing at Milwaukee, in the county of Milwaukee and State of Wisconsin, have invented new and useful Improvements in Electrical Regulators, of which the following is a full, clear, concise, and exact description, reference being had to the accompanying drawing forming a part of this specification.

This invention relates to electrical regulators and more particularly to regulators of the vibratory type.

An object of the invention is that of providing an improved and simplified regulator of such character.

Another object is that of providing such a regulator comprising regulative elements and electro-responsive control means therefor, and wherein provision is made for rendering operation of said control means independent of influence by the former elements, to thereby permit relatively light and sensitive construction and organization of said electro-responsive means while enabling construction of the regulating elements of such strength and ruggedness as the operative conditions thereof require.

Another object is that of providing a vibratory regulator wherein the permissible amplitude and power of vibration is increased with consequent increase in positiveness and reliability of operation of the device.

Other objects and advantages will herein-after appear.

According to the present invention it is proposed to provide a relay having contacts certain of which may vibrate continuously and at a fixed rate, said contacts having circuit connections whereby the same are adapted to effect regulation of a power or other circuit in accordance with the duration of that portion of each successive vibration within which said contacts are in engagement with one another. It is further proposed to provide for varying the duration of such portions of the successive vibrations in accordance with variations in the electrical condition to be controlled, the arrangement being such as to permit performance of the latter mentioned function unhampered by the operation of said relay.

More particularly it is proposed to provide for periodic relative positioning of the

co-operating contacts of the relay with reference to one another whereby the duration of engagement thereof for each vibration is increased or decreased in accordance with variations from a given standard of 60 the electrical conditions to be regulated, to thereby provide for counteracting such variations, the positioning means being periodically rendered operatively independent of the relay and each of the aforementioned 65 periodic actions occurring preferably once during each vibration of the relay.

In the accompanying drawing, wherein are illustrated certain of the embodiments which the invention may assume in practice— 70

Fig. 1 is a side elevational view thereof as adapted to the regulation of D. C. circuits, a proposed set of circuit connections being illustrated diagrammatically;

Fig. 2 is a similar view illustrating a 75 modified construction adapted to regulation of A. C. circuits;

Fig. 3 is a front elevational view of the construction illustrated in Fig. 2; while,

Fig. 4 is a detail view of a portion of said 80 construction.

Referring to Fig. 1 of the drawing, the same illustrates a vibratory relay comprising a vibrating contact 9 and a relatively stationary contact 10, the latter, however, 85 being electromagnetically positionable with reference to said former contact in a manner to be hereinafter described.

In practice said relay preferably comprises a magnetic frame 11 to be secured to 90 a suitable insulating panel 12 and provided with a core 13 surrounded by a coil 14. An armature member 15 is medially pivotally mounted at a point of said frame, one end of said armature member being arranged 95 to be attracted by the flux induced by said coil, the opposite end of said member being bent outwardly and formed to provide a knife edge 16. An elongated contactor 17, carrying the contact 9 at one end, is mounted 100 upon said armature member by means of a bearing 18 coacting with the knife edge 16 of the latter. A spring 19 is adjustably tensioned between the frame 11 and the contactor 17 in a known and obvious manner 105 for maintaining said contactor in the afore-described assembled relation upon the armature member and also for biasing the upper end of the latter away from the core 13. The relatively stationary contact 10 of the 110

relay is carried by a fixed stud 20 in co-operative relation to the contact 9.

The lower end of the contactor 17 is bent outwardly to provide a bearing for a further 5 contact finger 21, the latter being maintained and biased toward said contactor 17 and the armature member 15 by means of a compression spring 22, the latter being mounted and arranged in an obvious manner. An adjustable contact 23 is carried by and in insulated 10 relation to the lower end of the finger 21 for co-operation with a fixed contact stud 24 carried by the panel 12. Said latter contacts are adapted to control continuity of the energizing 15 circuit of coil 14, being adapted to open upon energization of said coil and consequent attraction of the armature 15 and to close following de-energization of said coil and resultant biased movement of said 20 armature. Thus assuming energization of said coil from a suitable source of electrical energy, such as the battery illustrated, it is apparent that the aforescribed relay is adapted to effect continuous vibratory coaction 25 of its contacts 9 and 10 at a rate which may be varied at will by means of the various adjustments aforementioned.

Considering now more specifically the structure and operation of the relatively 30 stationary contact 10, the same preferably comprises an elongated bolt having an enlarged head portion acting as the contact proper, said bolt being telescopically carried by and partially within the fixed stud 35 20, the latter being provided with a longitudinal bore with which the reduced portion of said bolt is adapted to make a loose working fit. Said stud is furthermore, interiorly recessed as illustrated and provided with 40 spaced opposed interior shoulders 26 and 27, whereas the enclosed portion of the contact 10 is preferably screw threaded to receive an adjustable nut or collar 28 the latter being adapted to co-operate with the shoulder 45 27 for limiting outward movement of the contact with reference to the stud. A compression spring 29 is further interposed between said nut and said shoulder for biasing 50 said contact inwardly with reference to said stud. A bifurcated member 30 is further carried by and in insulated relation to the upper portion of the armature 17, said member being adapted to straddle the reduced portion of the contact 10 and to coact with 55 the head of said contact whereby upon outward movement of said armature the same is adapted to draw said contact outwardly with reference to the stud 20, the spring 29 being compressed.

60 A wedge-shaped member 31 is carried partially within the recessed portion of the stud 20 and positioned between the shoulder 26 of said stud and the inner terminal portion of the contact 10 whereby upon partial withdrawal 65 of said wedge member the spring 29

serves to draw said contact away from the vibratory contact 9 whereas upon insertion of said wedge member further within said recessed portion of the stud said contact 10 is forced outwardly with reference to the latter and toward said vibratory contact.

An electro-responsive device is carried by the panel 12 and provides for automatically inserting or withdrawing said wedge member with reference to the stud 20 in accordance with variations in the electrical condition which it is desired to regulate.

In practice said device may advantageously comprise a magnetic frame 32 secured to the panel 12, a coil 33 having circuit connections rendering the same responsive in accordance with the electrical condition which it is desired to regulate and a reciprocating plunger 34 having a link 35 connecting the same with an oscillable lever 36 at an intermediate point of the latter, one extremity of said lever being pivotally connected to the upper end of the wedge member 31. The opposite end of said lever 36 is of cam formation as shown at 37, and is adapted to coact 85 with an adjacent surface 38 of the frame 32. An adjustable tension spring 39 serves to maintain said lever in the aforescribed assembled relation with reference to the frame and also to bias said lever against 90 movement in response to the force developed by the solenoid. The cam surface 37 is preferably designed with reference to the pull:curve characteristic of said solenoid and the tension characteristic of 100 the spring 39 to maintain throughout the working range of said lever substantially a definite proportionality of the opposing forces acting thereon.

The operation of the aforescribed device for regulating the electrical condition of a power circuit may be described as follows.

Assume that it is desired to regulate the output voltage of a generator 40 provided with a field rheostat 41, the solenoid coil 33 110 being connected across the generator output lines and the contacts 9 and 10 of the relay being adapted when engaged to short circuit the field rheostat, the acting coil 14 of the relay being connected across a battery 42 as indicated or optionally across the generator terminals, and the capacities 43 and 44 being connected as shown for reducing sparking by said relay.

The parts being connected as described, it is obvious that the relay will vibrate continuously at a rate determined by the adjustment thereof and that during each vibration the contacts 9 and 10 are in engagement with one another for a longer or shorter period determined by the position of the wedge member 31.

If at any time the voltage of the output circuit increases above the desired value the flux due to coil 33 overpowers the tension of

the spring 39 with consequent partial withdrawal of the wedge member 31 from between the shoulder 26 and the adjacent end of the contact 10. The spring 29 thereupon acts to force said contact within the stud 20 and away from the vibratory contact 9 thereby shortening the period of engagement of said contacts with consequent shortening of the periods during which the field rheostat is short-circuited. The field of the generator is thus weakened and the output voltage thereof correspondingly reduced.

Conversely a drop in voltage of the generator below the desired value serves to effect insertion of the wedge member further between the shoulder 26 and the contact 10 with consequent forcing of said contact toward the vibratory contact 9 and lengthening of the periods within which said contacts are in engagement. The periods during which the field rheostat is short-circuited are thus lengthened with consequent strengthening of the generator field and increase in value of its output voltage.

The regulator illustrated in Figs. 2, 3 and 4 while similar in principle to that aforescribed has nevertheless been modified to adapt the same to regulation of an electrical condition of an A. C. circuit. Also in said latter construction the vibratory elements are mechanically actuated although obviously the same may be actuated electro-magnetically if desired.

In said construction a stud 45 is fixed to a suitable insulating panel 46 and a resilient vibratory contactor 47 is medially pivotally mounted upon the free end of said stud, said contactor carrying at one end a contact 48 adapted to co-operate with a relatively stationary contact 49. The opposite end of said contactor is provided with a strike plate 50 to be engaged by a cam 51, the latter to be power driven at suitable speed by means such as the motor 52 illustrated. A spring 53 serves to bias said contactor toward its position wherein the co-operating contacts are separated.

The contact 49 is carried by a resilient element 54, the latter being terminally supported upon a projection 55 of the stud 45 and being moreover insulated from the latter and the parts connected therewith. The contactor 47 is provided at a point adjacent the contact 48 with a rigidly secured stud 56 projecting toward and preferably through the resilient element 54 and being provided therebeyond with an adjustable and lockable nut 57 whereby during biased movement of the contactor 47 the same is adapted to draw the free end of the element 54 and its contact 49 therewith. The stud 56 is insulated from one or the other of the contactor 47 and the element 54. Also

said member 54 carries at a point preferably substantially midway between the contact 49 and the point of support of said member 54 a rigidly secured abutment block 58 whereas a stud 59 is mounted upon the panel 46 and adapted to project therefrom toward and in alignment with said block 58 but in a terminally spaced relation thereto.

The electro-responsive means for varying the duration of the portion of each vibration during which the aforementioned contacts are in engagement with one another preferably comprise a device adapted to act upon the well known rotating disc meter principle and include an induction disc 60 together with torque magnets 61 and 62 for actuating the latter. A spring 63 or equivalent device is arranged to oppose and normally counter-balance the torque upon said disk due to said magnets. A wedge-shaped element 64 is secured to the disk 60 adjacent the periphery thereof and in a relation to be moved by and with said disc between the adjacent end of the stud 59 and the abutment block 58 for introducing a greater or lesser thickness of said wedge element therebetween, dependent upon the extent and direction of movement of said disc.

The operation of this construction may be described as follows, assuming connection of the torque magnets in a manner to render the torque upon the disc 60 variable in accordance with the electrical condition to be regulated, the contacts 48 and 49 being adapted to control the exclusion and inclusion of a field rheostat either in the A. C. generator or in the excitor therefor, and the motor 52 being operated for effecting vibration of the contactor 47 at the desired rate. Under the foregoing conditions at each revolution of the cam 51, the contact 48 is moved toward and into engagement with its co-operating contact 49, the period of such engagement depending upon the relative position of said latter contact as determined in turn by the position of the disc 60 and the wedge element 64. During movement of said contactor away from the element 54 the former is adapted by means of the aforescribed stud 56 to draw said element and the abutment block 58 away from the disc 60 and wedge element 63 thus providing within the period of each vibration a definite interval during which said disc and wedge element are entirely unrestrained and hence free to adjust themselves angularly in response to any variation in the electrical condition which it is desired to regulate.

It is also to be observed that in each of the aforescribed constructions the frequency of vibration of the relay is rendered independent of the electrical condition including frequency of the controlled circuit.

What I claim as new and desire to secure by Letters Patent is:

1. In an electrical regulator, the combination with a relatively stationary contact member of a contact adapted to effect vibratory coaction therewith for regulating an electrical condition of a circuit, of an element to be electromagnetically actuated in response to variations in such electrical condition for positioning said first-mentioned contact relatively to said vibratory contact to thereby vary the duration of engagement of said contacts during each vibration of the latter, means for moving said contact member to release said element during a portion of the vibratory cycle and associated means whereby said contact member is utilized for relieving said element of influence of the contact engaging action.
2. In an electrical regulator, the combination with a contact member, a cooperating contact and vibratory operating means therefor, of an electromagnetically operated element for positioning said contact member

and associated means to be controlled by 25 said operating means for moving said contact member out of and into engagement with said element during that portion of the vibratory cycle wherein the contact member and contact are out of engagement with each 30 other.

3. In an electrical regulator, the combination with a contact member, a cooperating contact and vibratory operating means therefor, of an electromagnetically operated ele- 35 ment for positioning said contact member, means tending to maintain said contact member in engagement with said element, and associated means to be controlled by said operating means for moving said contact 40 member away from said element after disengagement of said contacts and permitting return of said contact element prior to re-engagement of said contacts.

In witness whereof, I have hereunto sub- 45 scribed my name.

ERWIN R. STOEKLE.
